METHOD FOR FABRICATING PROPELLER
BLADES AND THE LIKE

John W. Smith, Philadelphia, Pa.

Application October 1, 1929, Serial No. 396,481

20 Claims. (Cl. 29—156.8)

My present invention relates to a machine and method for making aeronautical propeller blades, fabricated by combining three fundamentals, forging, longitudinal rolling and simultaneous twisting as a completed stage of fabricating a metal propeller blade and is applicable to and an improvement upon my co-pending U. S. patent application Serial No. 289,052, filed June 28, 1928, issued as Patent No. 1,840,059 on January 10, 1932, entitled Rolling machine.

The specific type of blade herein referred to is fabricated from a comparatively short billet and within the completed forging and longitudinal rolling period and is distinctively different from the heretofore used method of forming and twisting or shaping propeller blades after the forging period or after the cross sectional area and length have been prepared.

Attempts to fabricate propeller blades by forming, shaping and twisting prepared metal blanks after the required cross sectional area and length have been prepared by forging or rolling has resulted in structural weaknesses.

There are two important factors to be considered in making the best possible metallic aeronautical propeller blade suitable for modern high speed performance.

The first factor relates to the specific type of blade.

The second factor relates to the apparatus and method of fabricating the specific type of blade.

These two factors cannot be properly explained when treated as separate subject matter.

The above two factors must be combined in the manufacture of the best possible aeronautical propellers.

In my other application Serial No. 289,052 I showed a machine in which it was necessary to hand-tilt or set the die 15 at the time when the blank was inserted.

I now employ an automatic means in the form of small auxiliary rollers 63, Fig. 7, for positively controlling the tilting of the die 15 during the initial pass or passes and before the gauging rollers 1a and 1b make contact with the rails 15b of the tilting die.

Improved means, Figs. 4 and 6, comprising rod 44, crank 45a, rod 48, and racks 47a and 47b, are herein employed for adjustably setting the annular die 14 toward the other die as a substitute for the setting means controlled by the hand lever 71 in the machine of my other application.

As a modification I retain the fundamental which combines the forging, rolling and twisting operation of my other machine, but substitute

for the longitudinally reciprocating tilting die a second annular die and axially twist the metal blank instead of said die, or tilt the annular die and hold the blank.

These and other advantages of my present invention will appear from the following specification and drawings showing a preferred embodiment.

In these drawings:

Fig. 1 shows a comparatively short metal blank 10 suitable for forming two blades. Fig. 1B is a cross section of same.

Fig. 1A shows an initial forging operation applied to one of said blanks.

Fig. 2 is an end view combined with a plan 15 view of the finished blade, the latter also showing cross sections of the blade taken at various positions along its length.

Fig. 2A is a cross section partly in side elevation through the axis of the blade.

Fig. 2B is a diagram showing the component parts of one cycle of operation of the machine and the relative extents thereof.

Fig. 3 is a detail to illustrate the operation of the blank gripping mechanism as a means of holding the blank during forging and rolling.

Fig. 4 is a longitudinal vertical sectional view through the machine partly in elevation.

Fig. 5 is a transverse vertical sectional view relating to the toggle means and the vertical adjusting means therefor, the latter operable to vary the extent of the forging movements of the annular die.

Fig. 6 is a transverse vertical sectional view partly in elevation through the machine of Fig. 4 showing the driving gears of the machine, the means for controlling the extent of the forging movements of the annular die, and the means for operating the walking beam which reciprocates the tiltable die during rolling period.

Fig. 6A shows means for setting for first or second pass.

Fig. 7 is a transverse vertical sectional view partly in elevation on a larger scale than Fig. 4 showing the annular die and the transversely tiltable longitudinally reciprocating die in position for the final passes with a section of the propeller blade in the die cavity.

Fig. 8 shows crank pin adjustment for second pass.

Fig. 9 shows tension adjustment for gauging 50 rollers.

The remaining Figs. 10 to 16 show the double annular die modification of the machine as follows:

Fig. 10 is a view similar to Fig. 4 except that an annular die has been substituted for the longitudinally reciprocating die and shows the means for supporting and axially twisting the blank.

Fig. 11 is a transverse vertical sectional view partly in elevation through the part of the machine of Fig. 10 relating to the means for supporting and axially twisting the blank and 10 through the pitch-generating mechanism.

Fig. 12 shows right angle turning mechanism as a substitute for the mechanism of Fig. 11.

Fig. 12A is a plan view of the turning mechanism of Fig. 12.

Fig. 13 is a sectional view partly in elevation through the two annular dies and their related parts.

Fig. 14 is an end view of the annular dies partly in section and their relating parts.

Fig. 15 is a transverse vertical sectional view partly in elevation on a larger scale through the pitch generating mechanism.

Fig. 16 shows a substitute for the means of Figs. 13 and 14 by providing a tilting mounting 25 for one of said annular dies.

Fig. 17 shows a further substitute for the means of Figs. 13 and 14.

I will now describe the specific mechanism as a typical example for forging, rolling and simultaneously twisting the metal blank into the fabricated article but of course without limiting my invention to the details of said embodiment except as required by the appended claims in view of the prior art. The same reference numerals 35 indicate corresponding parts throughout.

The base 60, Fig. 4, of the machine supports columns 60a connected at the top by cap-yoke 60b. This supports the toggle means hereinafter described for giving vertical forging movement to 40 the head 58, the latter having sleeves 58a slideable on the columns 60a. This head 58 supports two bearings in which the ends of the shaft 8 are journaled as shown in Fig. 7. The annular die 14 is keyed to said shaft 8.

Fig. 15 is a die having a die cavity or recess in its upper surface corresponding to the shape of the blade or other object to be formed. The walls 15a bounding this die cavity are separated from the side portions 15b of the die by the flash recesses 6. Said side portions 15b, hereinafter called rails, at any given transverse section of the die are shown slightly higher (Fig. 7) than the side walls 15a of the die cavity to permit the excess metal from the blank to squeeze from between the annular 55 die 14 and the die 15 into the aforesaid flash recesses 6. The surface of the rails 15b and of the die-cavity walls 15a lie in an undulating twisted plane corresponding to the angular twist of the blade to be formed.

The die 15 is mounted for longitudinal reciprocation under the annular die 14 and for simultaneous lateral tilting movements so that the two dies cooperate on a plane which follows and ultimately is identical with the above described twist 65 in the rails and die.

Extra heavy toggle link construction is used to secure the necessary vertical forging pressure of the annular die 14 against the metal blank and the lower die 15. Thus the described cross-head 70 75 58 supporting said annular die is supported by toggle links 30a, and 30b, pivoted to the rockers 31a and 31b by pins 36, the links being pivoted to the crosshead by the pins 37. The rockers 31a and 31b are connected by link 38. The means for operating said toggle comprises an armed rock-

shaft 53, Fig. 4, suitably journaled in the machine housing 81 and 82 and having a left-hand arm for mounting the cam roller 49 and a right-hand arm connected by link 52 with the upper parts of the rockers 31a and 31b. When the circular faced cam 50 on the anti-clockwise rotating shaft 10 bears against the aforesaid cam roller 49, Fig. 4, it rocks the armed rock-shaft 53, pulls down on the link 52 and straightens the toggles which forces the annular die 14 with a powerful 10 forging movement into the metal blank. Then said annular die 14 remains in said down position while the walking beam 56 imparts reciprocating movement to the die 15. Said crosshead is not released until the lifting cam 51 carried 15 by cam shaft 10 contacts against the cam roller 54 mounted on an arm of the rock-shaft 53. By pushing upwardly the link 52 the toggles are unlocked and the roller die 14 is withdrawn from die 15.

Die 15 receives reciprocating movement through walking beam 56 hinged on pin 80 which is securely fastened into main housing 81 as shown in Fig. 6 and Fig. 8.

Crank pin 55c is journaled in a shoe slidably 25 guided in walking beam 56 as in my other application.

Crank pin 55c is a part of slide 55a (Fig. 6) mounted on the rotating cam shaft 10.

Adjusting screws 55b control the adjustment of 30 crankpin 55c shown in Figs. 4 and 6, and provide for the required length of travel for making long or short forgings.

It will thus be seen that when the shaft 10 is 35 driven, the walking beam 56 will be oscillated resulting in the longitudinal reciprocation of the die carriage 59 along with the cradle 20 and the die 15, supported upon said carriage. Only the lower end of said beam 56 is shown in Fig. 4, the rest of it being indicated merely by the broken 40 line 56 so as not to obstruct the drawings. Adjustable link 57 connects walking beam 56 with reciprocating carriage 59.

The walking beam construction provides an extended time element of 235° (compare Fig. 2B) for 45 the rolling stroke and a short time element for a quick return stroke of 125°.

Rack 59 in Figs. 4 and 7 is hinged by link 88 to 50 adjustable stud mounted in arm 89 which is fastened to and reciprocates with reciprocating carriage 59.

Rack 59 reciprocates in gear case 58a (Fig. 7) and is in mesh with gear wheel 64 which is secured to annular die shaft 8 by bolt 87. Annular die 14 is secured to shaft 8 by key 69. The herein described mechanism establishes a registration between the reciprocating die 15 and annular die 14 and provides for a vertical forging movement during the rest period of the reciprocating die 15.

Two or more automatic passes of different forging extent are provided and are made to function through the following mechanism.

In Figs. 4 and 5, toggle rockers 31a and 31b are 55 mounted on shafts 35a and 35b, supported at either end in eccentric bushings 34 (Fig. 5) which are journaled in supporting cap rocker 39 and securely held to shafts 35a and 35b.

Lever 40, shown in Fig. 5 (center line of same is 70 shown in Fig. 4) is secured on shafts 35a and 35b, and may be moved from position 42a to 42b shifting center from 53a and 53b, thus automatically setting the machine for the first and second pass respectively, thus automatically setting the pass 75

during lifting period C, shown in diagram Fig. 2B at a time when there is no pressure on the dies. In Figs. 4 and 6, shifting link 48 is shown to be hinged to cam rocker 53. Cross pin 48b forms a part of link 48 and operates in guide slot 69 (Fig. 6A and Fig. 6) and is used to shift pin 48b from rack hook 47a to 47b, and vice versa, the shifting medium is represented by lever 67. Tumble shaft 68 is pivoted into guide 69 as shown in Fig. 6A.

Teeth on racks 47a and 47b shown in Figs. 4 and 6 engage pinion 46, secured to crank shaft 45c. When rack 47a is pulled down as herein described crank pin 45 will be in position for the second pass. When rack 47b is pulled down crank pin 45 will be in position shown in dotted lines at 45b for the first pass.

Link 44 transmits from crank pin 45 to lever 40 the required movement for the first and second pass.

Fig. 8 shows how crank pin 45 is slidably fitted into the crank end of crank shaft 45a. Adjusting screw 45b is used for setting the crank throw to suit the required amount of reduction for the second pass.

In Fig. 4 if the throw of crank pin 45 is increased the arc between 53a and 53b will be increased. If the throw of crank pin 45 is diminished, the arc between 53a and 53b will be diminished. If lever 67 is not moved, the pass will be automatically repeated.

In most cases the second pass would be repeated as the final pass.

Fig. 7 shows the gauging rollers 7a and 7b bearing hard against the die rails 15b, which represents a requirement for the final pass in rolling to gauge thickness and unit weight.

Auxiliary rollers 63 are mounted in suitable sockets in brackets 62a and 62b secured to the main housing 60 and control the tilting of the die 15 when the gauging rollers 7a and 7b are withdrawn.

A large forging machine has considerable spring to be considered.

The second pass may result in the gauging rollers 7a and 7b being forced away from the rails 15b, where the blade is widest, thus requiring a repeating pass to finish to gauge thickness.

Fig. 9 shows the length of link 44 to be adjustable by means of right and left hand screw threads. This adjustment is made use of to secure the proper tension for gauging rollers 7a and 7b.

The described shifting of the arm 48 from one rack to the other may be made either by hand or automatically.

Fig. 7 shows how the die cradle 20 along with the die 15 is free to tilt to dotted line positions 61a and 61b to conform to the required pitch angles throughout the blade profile. The face of the die 15 is preferably machined on a special pitch-generating miller as shown in my U. S. patent application, Serial No. 268,208, filed June 4, 1929.

The diagram, Fig. 2B, indicates a typical example in the operation of my machine of vertical forging and longitudinal rolling divided into four periods A, B, C and D.

Period A shows the vertical forging movement to be substantially completed within the dwell period of walking beam 56 at the moment when the crank pin 55c is passing the neutral point of the stroke, said crank pin rotating in anti-clockwise direction. The rolling period B then takes place during 235° out of one complete rotation 75 or cycle of the crank pin. At the finish of the

longitudinal rolling movement, the annular die 14 is raised from the work, this being the lifting period C in the diagram. Within the full lift period D the machine may be stopped, if desired, by moving hand lever 78, Fig. 6, thus disengaging the clutch 76. At that time the annular die 14 will be raised sufficiently high to withdraw the finished blade and a new blank 10 may be inserted.

Fig. 1 shows a comparatively short, cylindrical, preferably rolled metal bar 10 sawed through on 10 a slant to form two blanks with taper ends 11, each suitable for being longitudinally rolled to the required length and cross section and simultaneously twisted into a propeller blade by my method and machine.

Fig. 1A shows the blank in position between the two dies 14 and 15. The vertical forging movement has forced die 14 in the direction of arrow 13 for the first pass. Space 12 between dotted line of annular die 14 and reciprocating die 15 20 represents the amount of reduction left for the second pass.

The stop 19 serves to locate the blank with relation to the dies and it also obstructs the flow of metal toward the hub end of the blank during 25 the forging operation. The blank is gripped by causing the jaws 16a and 16b to be forced into the blank.

This gripping takes place during the forging movement as follows: Shoulder 22 on roller 14 30 forces gripping jaws 16a and 16b to full gripping position as shown in Fig. 3.

Handle 17b is a means for unlocking toggle 18a and 18b and also lifts the forging out of the die 15 by imparting a movement to 16a and 16b shown 35 by dotted lines. Any suitable means can be used for gripping the blank at its near end.

I prefer to use this character and form of blank although it will be understood the same is not strictly essential. In other words, the proper distribution of the metal throughout the blank to form the blade by my method and machine is secured, preferably by sawing it off on an incline as shown at 11 in Fig. 1.

In this application as in my Patent No. 45 1,840,059, the metal is urged in a longitudinal direction at the moment of deforming, and each rolling pass starts at the required pressure and this required pressure is maintained throughout the rolling period.

Each pass starts off with a vertical die forging movement for preparing the heavy section of the blade at the butt end of the blank. Upon the completion of the vertical forging movement and without releasing it, a longitudinal rolling movement takes place at the required pressure extending lengthwise of the bar, thus preparing a longitudinal grain fibre in the blade structure with a simultaneous shaping and twisting of the blade. By my method and machine the finished 60 blade, Fig. 2, compared with the blank 10 is considerably elongated, preferably so that the grain fibre is extended longitudinally in the ratio of about one to three. The zone of the blade subject to the highest strains will possess the most 65 extension of grain fibre.

The above process of forging, rolling and twisting prepares in the blade the very best physical properties.

The face of the annular die 14 is shown channeled at 14a to prepare the upper face of the blade during the forging and rolling operations.

The metal of said blank is squeezed and rolled down into the cavity of the die 15. These forging and rolling passes are repeated until the die 75

cavity in its length, width, thickness and twist is completely filled. Fig. 4 shows the second stroke forging movement of the annular die completed and the machine about to begin the second pass rolling movement. This pass may be repeated as a final pass.

It will be seen that the described method and machine rolls the blade profile from a comparatively short billet, establishing the width, thickness, length and twist as a simultaneous operation. This is distinctively different from the prior art methods of preparing the angular twist of the blade after the length and cross sectional area has been prepared, said prior art methods resulting in a comparatively inferior finished blade.

My application Serial No. 289,052 has the equivalent vertical forging and longitudinal rolling movements, the operation of same was explained 20 in connection with a specially prepared short blank requiring considerable longitudinal rolling and only a slight amount of vertical forging.

This invention is herein further explained in connection with fabricating propeller blades from 25 plain round bar material which is less expensive.

The vertical-forging movement is herein used to eliminate the necessity of previously shaping the blank at the forging zone between lines 24 and 25 Fig. 2.

30 Figs. 2 and 2A show one type of finished blade adapted to be fabricated by my method and process. The round portion between the lines 23-24 is preferably finished by machining the blade. The zone between the lines 24-25 is die forged. 35 The zone between line 25 and the end 26 is die rolled to gauge cross section and unit weight including angular twist.

Forging, rolling and simultaneously twisting by using double annular dies

40 Fig. 10 makes use of the same fundamental vertical forging and horizontal rolling as shown in Figs. 1 to 9 inclusive, by substituting annular die 15c for horizontal die 15. Therefore, no further description is considered necessary.

Figs. 13 and 14 show the equivalent rack mechanism used for the registration of said annular dies.

Fig. 14 shows 59a and 59b to be hinged on wrist 50 pin 109 mounted in reciprocating carriage 110.

Connecting link 57 is also mounted on wrist pin 109 imparting motion from walking beam 56 to reciprocating carriage 110.

Annular die 15c, substitutes reciprocating die 55 15 shown in Figs. 7 and 4.

Fig. 16 shows annular die 15d mounted in non-reciprocating cradle 20a which is seated in main housing; in this event the pitch angle is generated on the annular die 15d, and would eliminate the use of pitch generating mechanism shown in Fig. 11. Gripping jaws 113 would be required to reciprocate without rotary motion. In this event 125, Fig. 11, would be set parallel to the reciprocating path, as shown in dotted line 125a.

Fig. 17 shows annular dies 15e and 14e to have the pitch angle generated on the face of both annular dies, in this modification annular dies are 70 not tiltably mounted and would be used with a non-rotating gripping mechanism for holding the blank.

The above annular dies have milled in their faces the blade profile.

75 The required pitch is generated by rotating the

gripping jaws with the following mechanism in the herein described manner.

Blank 10 (Fig. 1) is firmly held between gripping jaws 113 pivoted on pins 113a as shown in Fig. 10.

Toggle links 114 and rocker 115 are actuated by piston 117 through link 116.

Gripping jaws 113 and rocker 115 are mounted in sleeve 112, which is free to rotate in reciprocated housing 110.

Spur gear 118 is mounted on sleeve 112 and engages with pinion 119 which is fastened on pinion shaft 120.

Bevel pinion 121 is mounted on pinion shaft 120 and engages bevel gear 122 which is bolted to pitch generating arm 124 as shown in Fig. 10 and Fig. 11. Generating slide 125, Fig. 10, is adjustably mounted on arm 124 by means of pivot bolt 129 and bolt 128 in slotted hole 133.

Bracket 131 is fastened to main frame 68 for 20 supporting cross bar 126 in which shoe 127 is pivoted, as also shown in Fig. 9.

Housing 111 is provided with a pair of trunnions 108 and reciprocates with carriage 110.

Studs 109 are mounted on reciprocating carriage 110 to which forked link 57 is hinged and is reciprocated by walking beam 56.

Racks 59a and 59b are also hinged to the studs 109 and are actuated by the same motion.

Figs. 13 and 14 show how racks 59a and 59b 30 engage timing gear wheels 64a and 64b respectively. The annular dies 14 and 15c are securely mounted on shafts 8a and 8b. Gear wheels 64a and 64b are securely mounted on shafts 8a and 35 8b.

Rocking shoe 4 in Figs. 13 and 14 provides for the swinging of rack 59b during vertical forging movement of annular die 14.

Fig. 12 shows a modified movement which may be substituted for the pitch generating movement. Rocking head 137 is secured to bevel gear 122. Actuating link 133 is mounted on stationary cross bar 131.

The rocker head 137 has been rotated from pivot point 138 to position 139 at the end of the 45 stroke after the completion of the rolling movement.

Link 133 may be set to angle 134 by hand operated handle 135 for returning rocker head 137 to normal position thus causing gripping jaws 113 to receive right angle turns at the completion of each pass, making it possible to roll various tapered or special shapes.

I claim:

1. The method of making a propeller blade, 55 comprising rolling a billet of metal into rough blade shape by a series of complete rolling passes from the root portion to the tip portion of the blade, thereby creating flow lines conforming to the contour of the blade, and completing the 60 shaping of the blade by operations maintaining such flow line structure.

2. The method of making a propeller blade, 65 comprising deforming a billet of metal into rough blade shape by the repeated application of a deforming force progressively advancing from the root portion to the tip portion of the blade, thereby creating flow lines in the metal conforming to the contour of the blade and confined within the blade, and completing the shaping of the 70 blade by operations maintaining such flow line structure.

3. The method of making a propeller blade comprising gradually deforming a billet of metal into the shape of a tapering blade by applying 75

a deforming force to the metal, progressively advancing the point of application of force from the root portion to the tip portion of the blade, progressively applying the required force from 5 the root portion to the tip portion of the blade to gradually refine the grain structure throughout the length of the blade with a minimum of grain size contrast and to form flow lines conforming to the contour of the blade, and completing 10 the shaping of the blade by forging operations without increasing the grain size contrast or destroying the flow lines.

4. The method of making a propeller blade, which consists in rolling a billet of metal to prepare 15 longitudinal flow lines in it, rolling said billet into rough blade shape by a series of complete rolling passes from the root portion to the tip portion of the blade, thereby creating flow lines conforming to the contour of the blade, and completing 20 the shaping of the blade by operations maintaining such flow line structure.

5. The method of making a propeller blade, which consists in preparing longitudinal flow lines in a billet of metal by rolling, deforming said 25 billet into rough blade shape by the repeated application of a deforming force progressively advancing from the root portion to the tip portion of the blade, thereby creating flow lines in the metal conforming to the contour of the blade and 30 confined within the blade, and completing the shaping of the blade by operations maintaining such flow line structure.

6. The method of making a propeller blade, which consists in preparing longitudinal flow lines 35 in a billet of metal by rolling, gradually deforming said billet into the shape of a tapering blade by applying a deforming force to the metal, progressively advancing the point of application of said force from the root portion to the tip portion 40 of the blade, progressively applying the required force from the root portion to the tip portion of the blade to gradually refine the grain structure throughout the length of the blade with a minimum of grain size contrast and to form flow lines 45 conforming to the contour of the blade, and completing the shaping of the blade by forging operations without increasing the grain size contrast or destroying the flow lines.

7. The method of fabricating a propeller blade 50 and the like from a comparatively short metal blank, which consists in subjecting said blank to an initial forging operation, urging the metal in a longitudinal direction at the moment of deforming as a preparation for longitudinal rolling, subjecting said blank to longitudinal rolling, and simultaneously twisting the blank conformably 55 to the axial twist of the blade, whereby the physical properties of the blade are improved and a longitudinal fiber structure is incorporated 60 therein.

8. The method of claim 7, further characterized by repeating the cycle of operations therein set forth to further improve the physical properties and secure unit weight and precision in the 65 finished article.

9. The method of fabricating propeller blades and the like, which comprises applying a forging operation near one end of a metal blank in reduction of its thickness, substantially obstructing 70 the free flow of the metal during said forging operation towards the near end of said blank but not towards the far end, and applying rolling and shaping operations lengthwise of said blank thereby developing the longitudinal flow line to 75 conform to a predetermined die cavity.

10. The method of fabricating propeller blades and the like from a short taper ended metal blank, which comprises applying the required forging pressure near one end of the blank in reduction of its thickness, and applying rolling and shaping operations lengthwise of said blank without releasing the required forging pressure thereby developing the longitudinal flow line to conform to a predetermined die cavity. 5

11. The method of fabricating propeller blades 10 and the like, which comprises subjecting a short metal blank with one end tapered to a forging operation in reduction of its thickness, and to simultaneous rolling and shaping operations lengthwise of the blank starting from said reduced in thickness part and rolling towards said tapered end. 15

12. The method of fabricating a propeller blade and the like, which comprises sawing or otherwise cutting at an angle a rolled metal blank, subjecting said blank adjacent to the opposite end to a forging operation in reduction of its thickness, and starting from said reduced in thickness zone simultaneously rolling, shaping and twisting the blade to the required thickness. 20 25

13. A method of fabricating propeller blades or the like, which consists in placing a metal blank shorter than the finished blade between two dies formed with die cavities corresponding to the shape of the finished blade, at least one of the dies being a roller, forcing the two dies together with sufficient pressure to produce a forging effect on one part of the blank, thereby forming a portion of the blade adjacent its hub end, and then causing the roller die to press the blank against the other die while moving the blank relative to the roller without releasing the forging pressure, thereby rolling and drawing the metal toward the tip of the propeller blade, producing a favorable grain structure to conform to a pre-determined die cavity. 30 35

14. A method of fabricating propeller blades or the like, which comprises placing a metal blank shorter than the finished blade between two dies formed with die cavities corresponding to the shape of the finished blade, at least one of the dies being a roller, forcing the two dies together with sufficient pressure to produce a forging effect on one part of the blank, thereby forming a portion of the propeller blade adjacent its hub end, causing the roller die to press the blank against the other die while moving the blank relative to the roller without releasing the forging pressure, thereby rolling and drawing the metal toward the tip of the propeller blade, producing 40 45 50 55 a favorable grain structure and forcing the metal into the die cavities, and passing the blank through the dies a plurality of times, the distance between the dies being reduced on a subsequent pass. 60

15. A method of fabricating propeller blades or the like, which comprises severing a cylindrical piece of metal along a diagonal line, thereby producing a blank shorter than the finished blade and having a square-cut end and a tapered end, 65 placing the blank between two dies formed with die cavities corresponding to the shape of the finished blade, at least one of the dies being a roller, securely gripping the square-cut end of the blank, forcing the two dies together with sufficient pressure to form a portion of the hub end of the propeller blade, and then causing the roller die to roll over the blank toward the tapered end of the blank without releasing the forging pressure, thereby rolling and drawing the metal toward the 70 75

tip of the propeller blade, producing a favorable grain structure and forcing the metal into the die cavities.

16. A method of fabricating propeller blades or the like, which comprises placing a metal blank between a flat die and a roller die, anchoring one end of the blank at one end of the flat die, forcing the roller die against the blank adjacent the anchored end of the blank with sufficient pressure to produce a forging effect, thereby forming a portion of the propeller blade adjacent its hub end, subsequently causing the roller to move over the blank and the flat die without releasing the forging pressure, and simultaneously tilting the flat die relative to the roller die, thereby rolling and drawing the metal toward the tip of the propeller blade, producing a favorable grain structure and shaping the propeller blade.

17. A method of fabricating propeller blades or the like, which comprises placing a metal blank between two roller dies, gripping one end of the blank, forcing the roller dies together against the blank adjacent the gripped end of the blank with sufficient pressure to produce a forging effect, thereby forming a portion of the propeller blade adjacent its hub end, and subsequently passing the blank through the roller dies without releasing the forging pressure, thereby rolling and drawing the metal toward the tip of the propeller blade, producing a favorable grain structure and shaping the propeller blade.

18. A method of fabricating propeller blades or the like, which comprises placing a metal blank between two roller dies, the dies being formed with die cavities corresponding to the shape and pitch of the finished propeller blade, gripping one end of the blank, forcing the roller dies together against the blank adjacent the gripped end of the blank with sufficient pressure to produce a forging effect, thereby forming a portion of the propeller blade adjacent its hub end; and subsequently passing the blank through

the roller dies without releasing the forging pressure, thereby rolling and drawing the metal toward the tip of the propeller blade, producing a favorable grain structure and shaping the propeller blade.

19. A method of fabricating propeller blades or the like, which comprises placing a metal blank shorter than the finished blade between two dies formed with die cavities corresponding to the shape of the finished blade, at least one of the dies being a roller, the blank being contacted at the hub end by an abutment which obstructs flow of the metal, gripping the blank adjacent the hub end, causing the roller die to contact with the blank at a point adjacent the hub end with sufficient pressure to produce a forging effect and to force the metal into the die cavities, and then causing the roller die to roll to the blade tip at the required pressure, thereby die-pressing the metal at the hub end and rolling the blade from the hub to the tip by one continuous, uninterrupted process.

20. A method of fabricating propeller blades or the like, which comprises placing a metal blank shorter than the finished blade between two dies formed with die cavities corresponding to the shape of the finished blade, at least one of the dies being a roller, the hub end of the blank being placed against a stop, which serves to locate the blank relative to the dies and to obstruct flow of metal, gripping the blank adjacent the hub end, causing the roller die to contact with the blank at a point adjacent the hub end with sufficient pressure to produce a forging effect and to force the metal into the die cavities, and then causing the roller die to roll to the blade tip at the required pressure, thereby die-pressing the metal at the hub end and rolling the blade from the hub to the tip by one continuous, uninterrupted process.

JOHN W. SMITH.
